Primary Examiner — Dana K Weiland*Assistant Examiner* — Russell Carnell Smith, Jr.(74) *Attorney, Agent, or Firm* — Birch, Stewart, Kolasch & Birch, LLP(57) **CLAIM**

The ornamental design for an eartip, as shown and described.

DESCRIPTION

1. Eartip

1.1 : Perspective

1.2 : Rear perspective view

1.3 : Front

1.4 : Back

1.5 : Left

1.6 : Top

1.7 : Cross sectional

The right-side view is omitted because it is symmetrical to the left side view, reproduction 1.5; reproduction 1.7 is a cross-sectional view of the portion taken in the direction of line 1.7-1.7 in reproduction 1.3.

The broken lines in Reproduction 1.7 depict portions of the eartip that form no part of the claimed design.
